CIRCUIT BREAKER

Application filed June 27, 1927. Serial No. 201,937.

My invention relates generally to circuit breakers, and it is a purpose of my invention to provide a circuit breaker embodying a mechanism normally tending to open one or more switches with a delayed action, but restrained against such opening tendency by a certain condition existing in a prime mover, the mechanism being released when such condition changes to assume another condition, 10 and opening the switch or switches after an interval of time has elapsed, whereby the circuits controlled by the switches will be disrupted to prevent useless consumption of current whether the current is employed by the prime mover or some other element.

It is another purpose of my invention to provide a circuit breaker particularly adapted, although not necessarily, for disrupting the ignition and lighting circuits of a motor vehicle when its motor ceases operation, so that should the operator fail through inadvertence or otherwise to turn off the ignition of the motor or lights of the vehicle when left parked, for example, the circuit 20 breaker will function automatically to disrupt their circuits and thereby prevent exhausting of and possible injury to the battery of the vehicle.

It is also a purpose of my invention to provide a circuit breaker which embodies a run down device constantly acting to disrupt the ignition and lighting circuits of the vehicle, and capable of being controlled by the vehicle's motor in such manner that so long 30 as the motor is operating, the circuits will not be affected, but when the motor ceases operation the run down device will function automatically to disrupt the circuits, the run down device having means for regulating its 35 run down movement so that an interval of time will elapse after the motor ceases operation before the switches will be opened, to the end that should the motor "stall" the operator will have sufficient time to again start 40 it before the device functions to open the ignition switch.

It is another purpose of my invention to provide means for controlling the parking light circuit of the vehicle independently of the remaining circuits and operatively associ-

ated with the run down device in such manner that winding movement thereof will disrupt the parking light circuit, yet permitting the circuit to be manually established and maintained when the engine is not operating. 55

In the accompanying drawings,

Figure 1 is a view illustrating in vertical section one form of circuit breaker embodying my invention, and showing the manner in which the circuit breaker is associated with the engine of a motor vehicle to control the ignition and lighting circuits of the vehicle;

Figure 2 is a sectional view taken on the line 2-2 of Figure 1;

Figures 3, 4 and 5 are diagrammatic views 65 illustrating various positions occupied by the ignition and lighting switches in the operation of the circuit breaker;

Figure 6 is a fragmentary view illustrating another manner in which my circuit breaker 70 is adapted to be associated with the engine of the vehicle.

Fig. 7 is a diagrammatic view illustrating the manner in which my circuit breaker is adapted to be incorporated in conventional 75 ignition and lighting circuits of the motor vehicle.

Reference will now be had to the accompanying drawing, in which similar reference characters designate similar parts in each of 80 the several views.

For the purpose of illustration I have shown in the drawing one adaptation of my circuit breaker in which it is employed for the purpose of controlling the ignition and lighting 85 circuits of a motor vehicle, and is responsive to suction created by the motor when operating to maintain switches in these circuits closed, yet functioning automatically to open the switches and disrupt these circuits 90 when the motor ceases operation.

In its present embodiment my invention comprises a casing 10 enclosing a plurality of switches designated generally at S, S' and S², the switch S adapted to control the ignition 95 circuit of the motor, the switch S' the lighting circuit of the vehicle with the exception of the parking light circuit, which latter is adapted to be controlled by the switch S².

The switches S and S' comprise movable 100

contact arms 11 and 11^a, respectively, formed of flexible strap metal secured at one of their ends to studs 12 fixed to and insulated from the cover plate 25 of the casing 10, and normally urged into engagement with stationary contacts 14 and 14^a, respectively, also secured to and insulated from the rear wall.

The switch S² in the present instance comprises a contact arm 15 pivoted on and insulated from the cover plate 25 of the casing and adapted to be moved into or out of engagement with a stationary contact 16 by means of a rod 17 pivotally connected to the arm and having a slot 18 receiving a pin 19 secured to and insulated from the cover plate, the pin and slot connection permitting reciprocal movement of the rod. The rod is extended from one side of the casing 10 and provided with knob 20 for manual actuation of the switch.

From the movable contact arms and stationary contacts of the respective switches S, S' and S² extend suitable conductors 21, 22 and 23, respectively, which form part of their respective circuits so that the switches will be interposed in series in the circuits as clearly shown in Figure 7. The switch S is in series with the conductor 21 which leads from one side of a battery B and extends to the usual spark coil C from whence current is delivered to the distributor D and then to the spark plugs P which latter are grounded to complete the circuit to the other and grounded side of the battery B. The switch S' is in series with the conductor 22 which leads from one side of the battery B to the head-lights H and tail-light T; and also in series with the conductor 22 is the usual manually operable lighting switch S^a, so that in order to complete this circuit it is necessary that both the switches S' and S^a be closed. The switch S² is in series with the conductor 23 also leading from one side of the battery B and to the usual parking light L so that when the switch S² is closed this circuit will be completed to illuminate the parking light.

My circuit breaker, in the present instance, embodies a mechanism housed in the casing 10 and constituting a run down device for controlling the movements of the respective contact arms of the switches S, S' and S² in a manner to be hereinafter described. The run down device comprises a shaft 24 journaled in the rear wall 10 and cover plate 25 of the casing, which shaft is constantly urged to rotate in a counter-clockwise direction as viewed in Figure 1 by means of a coil spring 26 secured at one end to the shaft and at its other end to a stud 27 secured to the rear wall of the casing.

Fixed to the shaft 24 is an element E in the form of a disk of insulating material having a peripheral projection 28 constituting a cam which is adapted to engage and move the contact arm 11^a of the switch S'

out of engagement with its stationary contact 14^a to disrupt the lighting circuit of the vehicle. A second element E' forming part of a manually operable actuator is also in the form of a disk of insulated material rotatably mounted on the shaft 24 and provided with a peripheral projection 29 adapted to engage and move the contact arm 11 of the switch S out of engagement with its stationary contact 14 so as to disrupt the ignition circuit of the vehicle.

The elements E and E' are provided with inter-engaging pins 30 and 31, respectively, through the medium of which the element E' is adapted to be rotated by the element E in a counter-clockwise direction in response to rotation of the shaft 24 under the urging action of the spring 26 to engage their respective projections 29 and 28 with the contact arms of the switches S' and S, respectively, to move the contact arms and simultaneously open the switches.

The shaft 24 projects from the cover plate 25 and extending axially from the element E' and through the cover plate is a sleeve 32 to which is secured in any suitable manner an operating lever 33 by which the element E' is adapted to be manually moved from the position shown in Figures 1 and 3 to that shown in Figure 4. It will be noted that this movement of the operating lever effects corresponding movement of the element E to rotate the shaft 24 in a clockwise direction and wind the spring 26, through the medium of the inter-engaging pins 30 and 31, this movement of the elements causing their projections 29 and 28 to disengage the contact arms of the switches S' and S, respectively, and thereby permit the switches to close.

The extreme positions of the operating lever 33 are determined by stop pins 34 and 35 secured to the cover plate in the path of movement of the lever as is clearly shown in Figure 1. The element E' is provided with a laterally projecting pin 36 adapted to engage a stud 37 fixed to the rod 17 of the switch S² so that manual movement of the element E' from the position shown in Figure 1 to that shown in Figure 4 will move the rod in the direction of the arrow (Figure 1) and cause the contact arm 15 to disengage its contact 16 and thus open the switch S² upon closing of the switches S and S'.

Fixed to the shaft 24 is a ratchet wheel 38 engaged by a spring pressed pawl 39 pivoted at 40 on a gear 41 rotatably mounted on the shaft and meshing with a pinion 42 fixed to a second shaft 43 also journaled in the rear wall and cover plate of the casing 10. Fixed to the shaft 43 is a brake drum 44 with which a brake shoe 45 is adapted to have braking engagement. The brake shoe is pivotally mounted at 46 on one end of a lever 47 pivoted at 48 on the rear wall of the casing and extending from the latter for operative connec-

tion in the present instance to a pneumatic means including a diaphragm 49, by means of an arm 50 fixed to the diaphragm and pivotally connected to the extended end of the lever.

In the present embodiment of my invention, the diaphragm 49 is illustrated as forming one wall of the suction chamber 51 of a suction responsive device R, and extending from the chamber is a suction pipe 52 leading to the intake manifold I of the motor M of the vehicle as is clearly shown in Figure 1. When the motor is in operation the suction created in its intake manifold operates to flex the diaphragm 49 inwardly of the chamber 51 so as to exert a pull upon the lever 47 and cause the brake shoe 45 to have braking engagement with the brake drum 44, thus preventing rotation of the shaft 24 in its urged direction, through the medium of the pinion 42, gear 41, pawl 39 and ratchet wheel 38, yet permitting manual rotation of the shaft 24 in the other direction.

Fixed to the shaft 43 is a gear 53 meshing with a pinion 54 fixed to an escapement shaft 55 journaled in the rear wall and cover plate of the casing 10. Also fixed to the escapement shaft 55 is an escapement wheel 56 engaged by a weighted double escapement pawl 57 pivoted on a shaft 58 secured to the rear wall of the casing 10. This escapement or governing mechanism constitutes a means for regulating the speed of rotation of the shaft 24 under the unwinding action of the spring 26.

The operation of the circuit breaker is as follows:

It will be assumed that the motor M is not in operation and that the elements E and E' occupy the position shown in Figures 1 and 3 in which the ignition and lighting switches S and S', respectively, are held open by the projections 29 and 28, respectively, of the elements. The operating lever 33 is first manually moved from the position shown in Figures 1 and 3 to the position shown in Figure 4, thus rotating the element E' (fixed to the operating lever), and, through the medium of the inter-engaging pins 30 and 31 correspondingly rotating the element E and the shaft 24 to wind the spring 26. With the operating lever in the position shown in Figure 4, the elements E and E' will have been rotated sufficiently to disengage their projections 28 and 29, respectively, from the contact arms of the switches S' and S, respectively, thus permitting the contact arms to engage their respective stationary contacts 14 and 14^a to close the switches as is clearly shown in this figure.

As the ignition circuit is now completed through the switch S, the motor M may be started in the usual manner. With the motor in operation, the suction created in its intake manifold I will cause the brake shoe

45 to be moved into braking engagement with the brake drum 44 and hence, through the medium of the pinion 42, gear 41, pawl 39, and ratchet wheel 38, to restrain the shaft 24 from rotating under the urging action 70 of its spring 26, to thereby maintain the elements E and E' in the position shown in Figure 4 and the switches S and S' closed.

As shown in Fig. 7, the switch S constitutes the only controlling switch for the ignition circuit, and that although the lighting circuit is bridged through the switch S', the conventional manual control switch S^a for the individual lights of the vehicle is manipulated in the usual manner and will now be 75 operative to cause the headlights H and tail-light T to burn or be extinguished as desired.

Should the operator desire to stop the motor the lever 33 is moved from the position shown in Figure 4 to that shown in Figure 5, thus rotating only the element E' to cause its projection 29 to again engage and move the contact arm 11 to the position shown in the latter figure, thereby opening the ignition switch S and disrupting the ignition circuit. 80 Upon ceasing of the motor's operation, the brake shoe 45 will accordingly be disengaged from the brake drum 44, thus permitting the shaft 24 to rotate in response to the urging action of the spring 26, to thereby restore the element E to the position shown in Figure 1 and Figure 3, so that its projection 28 will again engage and move the contact arm 11^a to open the lighting switch S'. It will thus be clear that should the operator have failed 85 through inadvertence or otherwise to extinguish the lights of the vehicle by manipulation of the conventional manual control switch (previously mentioned) the disrupting of the lighting circuit will be automatically effected by the element E so that the lights will be extinguished and exhausting 90 of the battery of the vehicle from this source positively prevented.

In the event that the motor should "stall" 10 and the operator fail to disrupt the ignition circuit by manually moving the operating lever 33 from the position shown in Figure 4 to that shown in Figures 1 and 3, the movement of the element E just described will automatically actuate the element E' and the lever 33 through the medium of the inter-engaging pins 30 and 31 so that both of the elements will be restored to the position shown in Figure 1, to accordingly open both the ignition and lighting switches, thus rendering it impossible for either of the switches to remain closed after the motor ceases operation and unnecessarily discharging or possibly damaging the battery.

As the ratchet wheel 38 is fixed to the shaft 24, it will be clear that upon rotation of the shaft in response to the urging action of the spring 26, the gear 41 will be driven through the pawl 39, thus rotating the shafts 43 and 100

55 through the connecting train of gearing, and driving the escapement wheel 56, which, with its pawl 57, functions to regulate the speed of rotation of the shaft 24, to the end 5 that an interval of time will elapse after the motor ceases operation before the shaft 24 has been rotated sufficiently to cause the elements E and E' to open the switches S and S'. This delayed action of the run down device 10 is of particular advantage should the motor "stall" as the operator will have sufficient time to again start the motor before the ignition switch is automatically opened, thus eliminating the necessity of the operator 15 manually moving the operating lever 33 to switch closing position every time the motor stalls.

As previously described, the rotation of the element E' by the operating lever 33 to 20 the position shown in Figure 4 will cause movement of the rod 17 through the medium of the pin 36 and stud 37 to open the switch S² so that when the switches S and S' are 23 closed the switch S² will automatically be opened to disrupt the parking light circuit, thus preventing the unnecessary burning of the parking light P during operation of the vehicle over the road. However, when the element E' occupies the position shown in 28 Figures 1 and 3, the operator can press upon the knob 20 to close the switch S², and thus burn the parking light when the switches S and S' are open and the vehicle is parked.

In Figure 6 I have illustrated the manner in which the run down device is adapted 33 to be associated with the motor when it is desired to employ its oil pump (not shown) to control the operation of the device. In this instance a pipe 60 leading from the pressure side of the oil pump is connected to the suction responsive device R so as to be in communication with its chamber 51. It will be clear that as long as the motor is in operation the pressure created in the chamber 51 by the 45 oil pump will cause the diaphragm 49 to be flexed outwardly of the chamber, and through the arms 50 and lever 47 maintain the brake shoe 45 in braking engagement with the drum 44.

50 Although I have herein shown and described only one form of circuit breaker embodying my invention, it is to be understood that various changes and modification may be made therein without departing from the 55 spirit of the invention and the spirit and scope of the appended claims.

I claim as my invention:

1. A circuit breaker comprising a switch, a manually operable actuator for closing the 60 switch, a run down device operatively associated with the actuator for winding thereby in response to movement of the actuator to close the switch, said device, when wound, constantly acting to open the switch, and means adapted for association with a prime 65

mover to restrain said device from acting so long as the prime mover is in operation, whereby when the prime mover ceases to operate, said device will operate the actuator to open the switch. 70

2. A circuit breaker comprising a switch, a run down device constantly acting to open the switch, and means adapted for association with a prime mover to restrain said device from acting so long as the prime mover is 75 in operation, whereby when the prime mover ceases to operate, said device will act to open the switch, said last means comprising a brake drum operatively associated with said device, a brake shoe adapted to engage said 80 drum, a diaphragm operatively connected to said shoe and adapted to respond to pressure created by the prime mover to effect engagement of said shoe with said drum. 85

3. A circuit breaker comprising a switch, a run down device constantly acting to open the switch, and means adapted for association with a prime mover to restrain said device from acting so long as the prime mover is 90 in operation, whereby when the prime mover ceases to operate, said device will act to open the switch, said last means comprising braking means operatively associated with the run down device and active so long as the prime mover is in operation, and means 95 operatively associated with the braking means for rendering the latter inactive when operation of the prime mover ceases. 100

4. A circuit breaker comprising a pair of switches adapted respectively to control ignition and lighting circuits of a motor vehicle, a device normally tending to move to one position to open the lighting switch and movable to a second position to close the lighting switch, a manually operable actuator 105 movable to one position to open the ignition switch and to another position to close the ignition switch, means operable when said device moves to switch opening position to move said actuator to its switch opening position 110 and operable when said actuator is moved to its switch closing position to move said device to switch closing position, and means adapted to be controlled by the vehicle's motor, operable when the motor is in operation to 115 restrain said device from acting to open the lighting switch. 120

5. A circuit breaker comprising a pair of switches adapted respectively to control ignition and lighting circuits of a motor vehicle, a device normally tending to move to one position to open the lighting switch and movable to a second position to close the lighting switch, a manually operable actuator movable to one position to open the ignition 125 switch and to another position to close the ignition switch, means operable when said device moves to switch opening position to move said actuator to its switch opening position and operable when said actuator is moved to 130

- its switch closing position to move said device to switch closing position, means adapted to be controlled by the vehicle's motor, operable when the motor is in operation to restrain said device from acting to open the lighting switch, and rendering the device free to act to open the lighting switch when operation of the motor ceases, and means for so regulating the movement of said device to its switch opening position as to cause an interval of time to elapse after the motor ceases operation before the switches will be opened. 5 70
6. A circuit breaker comprising a pair of switches adapted respectively to control ignition and lighting circuits of a motor vehicle, rotary means movable to one position to open the lighting switch and to another position to close the lighting switch, spring means constantly acting to move the rotary means to its switch opening position, a rotary manually operable actuator movable to one position to open the ignition switch and to another position to close the ignition switch, co-acting means on the rotary means and actuator, operable in response to movement of the rotary means to switch opening position to move the actuator to its switch opening position and operable in response to movement of the actuator 10 80
- 20 to switch closing position to move the rotary means to its switch closing position, and means adapted for association with the vehicle's motor, responsive to suction created by the motor when in operation, to retain the rotary means in its switch closing position against the action of the spring means. 25 90
7. A circuit breaker as embodied in claim 4 wherein the first mentioned means is correlated with the device and actuator in such manner that the actuator can be moved to its switch opening position independent of movement of the device to its switch opening position. 40 95
8. A circuit breaker as embodied in claim 4 including a switch adapted to control a parking light circuit of the vehicle, and means operatively associated with the parking light switch and actuator for moving the parking light switch to open position upon movement 45 100
- 50 of the actuator to its switch closing position. 10. A circuit breaker comprising a pair of switches adapted respectively to control ignition and lighting circuits of a motor vehicle, a device normally tending to open the lighting switch, manually operable means for opening and closing the ignition switch, means 55 110
- 60 operable upon opening of the lighting switch, to actuate said manually operable means and cause the latter to open the ignition switch, and operable upon closing of the ignition switch by the manually operable means to close the lighting switch against the normal tendency of the device, and means adapted to be controlled by the vehicle's motor to restrain said device from opening the lighting switch when the motor is in operation. 65 115
11. A circuit breaker as embodied in claim 10 wherein the means for actuating the manually operable means is so correlated with the latter and said device that the manually operable means can be actuated to open the ignition switch when the lighting switch is maintained closed by the motor controlled means. 70 120
12. A circuit breaker as embodied in claim 10 including a switch adapted to control a parking light circuit of the vehicle, and means operatively associated with the parking light switch and manually operable means for opening the parking light switch upon actuation of the manually operable means to close the ignition switch. 75 125
13. A circuit breaker comprising a pair of switches adapted respectively to control ignition and lighting circuits of a motor vehicle, a device normally tending to open the lighting switch, means adapted to be controlled by the vehicle's motor for restraining said device from acting to open the lighting switch when the motor is in operation, and means operable in response to opening of the lighting switch to open the ignition switch. 80 130
14. A circuit breaker comprising a pair of switches adapted respectively to control ignition and lighting circuits of a motor vehicle, a device normally tending to open the lighting switch, means adapted to be controlled by the vehicle's motor for restraining said device from acting to open the lighting switch when the motor is in operation, manually operable means for opening and closing the ignition switch, and means operable in response to opening of the lighting switch, to open the ignition switch, yet rendering the latter free to be opened by the manually operable means while the lighting switch is maintained closed. 85 135
15. A circuit breaker comprising a pair of switches adapted respectively to control ignition and lighting circuits of a motor vehicle, a device normally tending to open the lighting switch, means adapted to be controlled by the vehicle's motor for restraining said device from acting to open the lighting switch when the motor is in operation, means operable in response to opening of the lighting switch to open the ignition switch, a third switch adapted to control a parking light circuit of the vehicle, and means operable in response to closing of the ignition switch to open the parking light switch. 90 140
16. A circuit breaker comprising a pair of switches adapted respectively to control igni- 95 145

tion and lighting circuits of a motor vehicle, a device normally tending to open the lighting switch, means adapted to be controlled by the vehicle's motor for restraining said device from acting to open the lighting switch when the motor is in operation, manually operable means for opening and closing the ignition switch, means operable in response to opening of the lighting switch, 10 to open the ignition switch, a third switch adapted to control a parking light circuit of the vehicle, and means operable in response to closing of the ignition switch by the manually operable means to open the parking light switch.

17. A circuit breaker comprising a switch, a device for opening the switch, a manually operable actuator for opening and closing the switch and so operatively connected to 20 said device as to render the latter operative to tend to open the switch when the actuator is moved to close the switch, and means adapted for association with a prime mover to restrain said device from opening the switch when the prime mover is in operation.

18. A circuit breaker comprising a switch, a device for opening the switch, a manually operable actuator for opening and closing 30 the switch and so operatively connected to said device as to render the latter operative to tend to open the switch when the actuator is moved to close the switch, yet rendering the actuator free to open the switch independently of the device, and means adapted for association with a prime mover to restrain said device from opening the switch when the prime mover is in operation.

19. A circuit breaker comprising a pair of 40 switches, each of which includes a movable contact arm and a stationary contact, a shaft, a spring connected to the shaft for constantly urging the latter to rotate in one direction, an element fixed to the shaft and having means 45 adapted during rotation of the shaft in its urged direction to engage and move the contact arm of one of the switches and open its contacts, a manually operable actuator comprising a second element rotatable on the 50 shaft and having means adapted to engage and move the arm of the other switch to open its contacts, an operative connection between the elements for transmitting movement of one element to the other so that movement of the first element in response to rotation of 55 the shaft in its urged direction will impart corresponding movement to the second element and thereby open the contacts of both switches and manual movement of the second 60 element in the other direction will correspondingly move the first element to wind said spring and close the contacts of both switches and means adapted for association with a prime mover operable when the latter 65 is in operation to restrain the shaft against

movement in its urged direction and thereby maintain the switches closed, whereby when the prime mover ceases operation the spring will be free to rotate the shaft, and through the medium of the elements open the switches.

20. A circuit breaker comprising a pair of switches, each of which includes a movable contact arm and a stationary contact, a shaft, a spring connected to the shaft for constantly 70 urging the latter to rotate in one direction, an element fixed to the shaft and having means adapted during rotation of the shaft in its urged direction to engage and move the contact arm of one of the switches and open its contacts, a manually operable actuator comprising a second element rotatable on the 75 shaft and having means adapted to engage and move the arm of the other switch to open its contacts, an operative connection between the elements for transmitting movement of one element to the other so that movement of the first element in response to rotation of the shaft in its urged direction will impart 80 corresponding movement to the second element and thereby open the contacts of both switches and manual movement of the second element in the other direction will correspondingly move the first element to wind 85 said spring and close the contacts of both switches, a ratchet fixed to the shaft, a gear fixed to the shaft, a pawl carried by the gear and engaging the teeth of the ratchet so as to rotate the gear in response to movement of the shaft in its urged direction yet permitting 90 movement of the shaft in the other direction independently of the gear to wind the spring, and means adapted for association with a 95 prime mover operable when the latter is in operation to restrain the gear against movement and thereby maintain the switches closed, whereby when the prime mover ceases 100 operation the spring will be free to rotate the shaft and gear and through the medium of the elements, open the switches.

21. A circuit breaker comprising a pair of switches, each of which includes a movable contact arm and a stationary contact, a shaft, a spring connected to the shaft for constantly 105 urging the latter to rotate in one direction, an element fixed to the shaft and having means adapted during rotation of the shaft in its urged direction to engage and move the contact arm of one of the switches and open its contacts, a manually operable actuator comprising a second element rotatable on the 110 shaft and having means adapted to engage and move the arm of the other switch to open its contacts, an operative connection between the elements for transmitting movement of one element to the other so that movement of the first element in response to rotation of the shaft in its urged direction will impart 115 corresponding movement to the second element and thereby open the contacts of both switches and manual movement of the second element in the other direction will correspondingly move the first element to wind said spring and close the contacts of both switches, an operative connection between the elements for transmitting movement of one element to the other so that movement of the first element in response to rotation of the shaft in its urged direction will impart 120 corresponding movement to the second element and thereby open the contacts of both switches and manual movement of the second element in the other direction will correspondingly move the first element to wind said spring and close the contacts of both switches, an operative connection between the elements for transmitting movement of one element to the other so that movement of the first element in response to rotation of the shaft in its urged direction will impart 125 corresponding movement to the second element and thereby open the contacts of both switches.

switches and manual movement of the second element in the other direction will correspondingly move the first element to wind said spring and close the contacts of both switches, a ratchet fixed to the shaft, a gear fixed to the shaft, a pawl carried by the gear and engaging the teeth of the ratchet so as to rotate the gear in response to movement of the shaft in its urged direction yet permitting movement of the shaft in the other direction independently of the gear to wind the spring, a second shaft operatively connected to the gear, a brake drum on the second shaft, a brake shoe adapted to engage the drum, and a diaphragm operatively connected to said shoe adapted for association with a prime mover in a manner to respond to suction created by the prime mover when in operation to maintain said shoe in engagement with said drum to thereby restrain the first shaft from movement and maintain the switches closed, whereby when the prime mover ceases operation the shoe will disengage the drum and render the shaft free to move to its urged position and open the switches.

22. A circuit breaker comprising a pair of switches, each of which includes a movable contact arm and a stationary contact, a shaft, a spring connected to the shaft for constantly urging the latter to rotate in one direction, an element fixed to the shaft and having means adapted during rotation of the shaft in its urged direction to engage and move the contact arm of one of the switches and open its contacts, a manually operable actuator comprising a second element rotatable on the shaft and having means adapted to engage and move the arm of the other switch to open its contacts, an operative connection between the elements for transmitting movement of one element to the other so that movement of the first element in response to rotation of the shaft in its urged direction will impart corresponding movement to the second element and thereby open the contacts of both switches and manual movement of the second element in the other direction will correspondingly move the first element to wind said spring and close the contacts of both switches, means adapted for association with a prime mover operable when the latter is in operation to restrain the shaft against movement in its urged direction and thereby maintain the switches closed, whereby when the prime mover ceases operation the spring will be free to rotate the shaft, and through the medium of the elements, open the switches, and means for regulating the movement of the shaft in its urged direction so that an interval of time will elapse after the prime mover ceases operation before the switches will be opened.

23. A circuit breaker comprising a pair of switches, each of which includes a movable

contact arm and a stationary contact, a shaft, a spring connected to the shaft for constantly urging the latter to rotate in one direction, an element fixed to the shaft and having means adapted during rotation of the shaft in its urged direction to engage and move the contact arm of one of the switches and open its contacts, a manually operable actuator comprising a second element rotatable on the shaft and having means adapted to engage and move the arm of the other switch to open its contacts, an operative connection between the elements for transmitting movement of one element to the other so that movement of the first element in response to rotation of the shaft in its urged direction will impart corresponding movement to the second element and thereby open the contacts of both switches and manual movement of the second element in the other direction will correspondingly move the first element to wind said spring and close the contacts of both switches, means adapted for association with a prime mover operable when the latter is in operation to restrain the shaft against movement in its urged direction and thereby maintain the switches closed, whereby when the prime mover ceases operation the spring will be free to rotate the shaft, and through the medium of the elements, open the switches, a third switch comprising a movable contact arm and a stationary contact, and an operative connection between the contact arm and said second element for opening said third switch when said second element is moved to close its respective switch.
